UNITED STATES PATENT OFFICE.

WILBERFORCE BEECHER HAMMOND, OF AUBURNDALE, MASSACHUSETTS.

COMBINED HEATING AND SPRINKLER SYSTEM.

1,316,541.

Specification of Letters Patent. Patented Sept. 16, 1919.

Application filed March 7, 1919. Serial No. 281,286.

To all whom it may concern:

Be it known that I, WILBERFORCE BEECHER HAMMOND, a citizen of the United States, residing at Auburndale, in the county of 5 Middlesex and State of Massachusetts, have invented certain new and useful Improvements in Combined Heating and Sprinkler Systems; and I do hereby declare the following to be a full, clear, and exact description 10 of the invention, such as will enable others skilled in the art to which it appertains to make and use the same.

This invention relates to combined heating and sprinkler systems in which a circulation 15 of hot water may be maintained through the distributing pipes of an automatic sprinkler system.

The primary object of the invention is to provide improved means for preventing the 20 communication of heat from the circulating water to the sprinkler heads so that a temperature which is effective for heating purposes may be maintained in the circulation pipe without danger of raising the temperature 25 at the sprinkler heads beyond a safe point.

To this end the present invention contemplates connecting the sprinkler heads with the circulation pipe by means of offset 30 portions each of which is provided with means in the nature of a check valve permitting water to enter the offset but obstructing its return into the circulation pipe, and also permitting a substantially unobstructed 35 discharge of water through the offset upon the release of the sprinkler head. It is preferred to further insure against circulation 40 of water in the offset by confining therein, between the valve and the sprinkler head, a permeable mass of material, such as flaky graphite.

The invention further consists in certain novel features of construction and arrangement of parts tending to produce a more 45 compact and better looking system, and which will be hereinafter described and defined in the appended claims.

The invention will be readily understood 50 from an inspection of the accompanying drawing illustrating the preferred embodiment of the invention and the following detailed description of the construction there- 55 in shown.

In the drawing, Figure 1 is a view in side 55 elevation of a portion of a combined heat-

ing and sprinkler system; Fig. 2 is a detail view in vertical longitudinal section of one of the sprinkler offsets; and Fig. 3 is a sectional view taken on the line 3—3 of Fig. 2.

As shown in the drawing a portion of the 60 pipe through which the hot water circulates and which also serves to supply the sprinkler heads is indicated at 5 and consists of substantially horizontal sections that are coupled together by T's 6. Extending upwardly 65 from each T is the sprinkler offset 7 which is connected at its upper end by means of a T-shaped coupling member 8 with a sprinkler head 9 which may be of any suitable or usual construction. The sprinkler offsets 7 70 are so curved that they extend only a short distance above the circulating pipe 5, thus permitting the latter to be arranged near the ceiling of the compartment in which the system is to be installed.

In the construction shown, the check valves with which the sprinkler offsets are provided severally consist of a ball 10 which is arranged to be seated normally on a valve seat 11 that is formed in the T 6, surrounding the opening which affords communication between the circulation pipe and the offset. In order to prevent conduction of heat through the valve the ball 10 consists of a hollow shell which is filled with asbestos 80 or other non-conducting material. The function of the check valve is to permit water from the circulation pipe to enter the offsets and to obstruct its return into the circulation pipe and thus to prevent circulation 85 of the water within the offsets.

As an additional means for insuring that no circulation of water shall take place in the offsets, a quantity of flaky graphite, sand, or other granular material is introduced into each of the offsets after the ball has been positioned on the valve seat. The water which is permitted to enter the offsets, thoroughly permeates the mass of material contained therein, producing a mixture 95 which is indicated at 12, in Fig. 2, and which is of sufficient density to resist relative motion of its particles and thereby prevent circulation within the offsets but which is at the same time fluid enough so that it will 100 not stick in the offsets when the sprinkler heads are released, but will be easily and quickly forced therethrough and discharged through the sprinkler heads.

Upon release of a sprinkler head the mix- 110

ture of water and the granular material will be quickly and easily forced through the offset by the pressure of the water in the system, until the mixture is all discharged from the 5 sprinkler head, and the ball will be carried up through the offset and deposited in a pocket 13 which is formed in the coupling member 8 opposite the end which is connected with the offset. The curve of each offset is of suffi- 10 ciently long radius to insure that neither the mixture nor the ball will stick in the offset. In order to prevent the escape of the ball through the open sprinkler head the interior surface of the coupling member 8 is formed 15 with a plurality of longitudinal ribs 14, as shown in Fig. 3, which closely confine the ball and guide it into the pocket 13. With the ball thus lodged in the pocket 13, the escape of the water is unobstructed. The 20 ball may be replaced on the valve seat and the offset refilled with flaky or granular material by removing a plug 15, which normally closes an opening in the coupling member 8 opposite the upper end of the 25 offset.

Heretofore offsets of considerable horizontal length have necessarily been employed, in order to prevent communication of heat to the sprinkler heads by circulation 30 of the heated water in the offsets, and also in order that trapped gases may accumulate in the offsets in sufficient quantity to have a heat insulating effect.

For these purposes it has also been found 35 necessary, heretofore, to provide upwardly branching offset pipes, terminating in dead ends having a horizontal component of offset from the junction with the circulation pipe which, measured along the offset, is 40 materially greater than the vertical component. The above described means for protecting the sprinkler heads from the heat of the circulating water permits the use of shorter offsets and accordingly there is less 45 danger of the offsets becoming broken off or injured and the general appearance of the system is improved.

Any suitable form of check valve which 50 will open upon the release of the sprinkler head so as not to obstruct the flow of water through the offset, may be used in place of the ball check valve illustrated.

Various kinds of granular or flocculent material may be utilized in the offsets, it being 55 essential only that the material used will not cake or harden from heat and will fill the offset in such a manner that the water will readily percolate through the mass to render it capable of being easily discharged 60 from the offset upon the release of the sprinkler head. The use of flaky graphite however is preferred because of its low friction qualities which permit it to be easily and quickly forced through the offset. It should 65 be understood, moreover, that the use of any

such material in the offsets is not considered essential to the broader features of the invention, inasmuch as it may be found that sufficiently good results will be obtained by the use of check valves alone. It is also 70 pointed out that the present invention is not limited to any particular arrangement or form of the sprinkler offsets inasmuch as they may be of such form or so arranged with respect to the circulation pipe as may 75 be found most desirable.

Having thus explained the nature and scope of the invention and described in detail the preferred form thereof, what is claimed as new is:—

1. A combined heating and sprinkler system having, in combination, a pipe for the circulation of heating water, sprinkler offsets branching from said pipe, sprinkler heads connected with the offsets, and means 80 within the offsets for normally preventing circulation of water therein and adapted to permit a substantially unobstructed discharge of water when the sprinkler heads are released.

2. A combined heating and sprinkler system having, in combination, a pipe for the circulation of heating water, a plurality of sprinkler offsets branching from said pipe, sprinkler heads connected with the offsets, and means 90 within the offsets for preventing circulation of water therein and adapted to be expelled from the offsets upon the release of the sprinkler heads.

3. A combined heating and sprinkler system having, in combination, a pipe for the circulation of heating water, a plurality of sprinkler offsets branching from said pipe, sprinkler heads connected with the offsets, and a permeable mass of material normally 100 contained in each offset for preventing circulation of water therein.

4. A combined heating and sprinkler system having, in combination, a pipe for the circulation of heating water, a plurality of 105 sprinkler offsets branching from said pipe, a sprinkler head connected with each offset, a mass of granular substance normally confined in each offset to prevent circulation of water therein and adapted to be discharged 110 with the water upon the release of the sprinkler head connected therewith, and means for preventing said granular material from entering the circulation pipe and for permitting the entrance of water from the circulation pipe into the offset.

5. A combined heating and sprinkler system having, in combination, a pipe for the circulation of heating water, a plurality of 115 sprinkler offsets branching from said pipe, a sprinkler head connected with each offset, and a device in the offset between the sprinkler head and circulation pipe normally closing the offset and constructed and arranged to open communication between the 120

130

circulation pipe and the offset for the substantially unobstructed flow of water when the sprinkler head opens.

6. A combined heating and sprinkler system having, in combination, a pipe for the circulation of heating water, a plurality of sprinkler offsets branching from said pipe, a sprinkler head connected with each offset, and a normally closed check valve in the offset spaced from the sprinkler head to secure a dead column of water between the valve and the sprinkler head and adapted to open toward the sprinkler head when said head opens to permit a substantially

unobstructed flow of water from the circulation pipe through the head. 15

7. A combined heating and sprinkler system having, in combination, a pipe for the circulation of heating water, a plurality of sprinkler offsets branching from said pipe, a sprinkler head connected with each offset, 20 a check valve in each offset so constructed as to be substantially non-conductive of heat and adapted to permit water to enter the offset from the circulation pipe but to obstruct the return of the water.

WILBERFORCE BEECHER HAMMOND.
